UNITED STATES PATENT OFFICE.

HENRY B. NICHOLS, OF PHILADELPHIA, PENNSYLVANIA.

RAILWAY-TRACK STRUCTURE.

SPECIFICATION forming part of Letters Patent No. 655,349, dated August 7, 1900.

Application filed May 1, 1900. Serial No. 15,057. (No model.)

To all whom it may concern:

Be it known that I, HENRY B. NICHOLS, a citizen of the United States, residing at the city of Philadelphia, in the county of Philadelphia and State of Pennsylvania, have invented certain new and useful Improvements 5 in Railway-Track Structures, of which the following is a specification.

My invention has relation to an improvement 10 in railway-track structures, such as frogs, switches, and crossings; and in such connection it relates more particularly to the construction and arrangement of such a structure.

The principal object of my invention is to 15 provide a frog, switch, crossing, or other track structure wherein the hardened plate or block, forming a continuation of the bearing-surfaces of the crossing-rails, is adapted to 20 be supported and secured in the casting locking the rails together by a soft-metal filling, which serves not only as a cushion or support for the hardened plate in the casting, but also 25 as the sole means for locking said plate in its required position in said casting.

My invention, stated in general terms, consists of a track structure constructed and arranged in substantially the manner herein-after described and claimed.

The nature and scope of my invention will 30 be more fully understood from the following description, taken in connection with the accompanying drawings, forming part hereof, in which—

Figure 1 is a top or plan view of a railway-crossing embodying main features of my invention. Fig. 2 is a cross-sectional view on the line $x-x$ of Fig. 1. Fig. 3 is a sectional view on the line $y-y$ of Fig. 1. Fig. 4 is a 35 view similar to Fig. 2, but illustrating the method of forming or casting the cast section to the rails; and Fig. 5 is a perspective view of the core or chill illustrated in Fig. 4.

In the drawings the improvement is illustrated 40 as applied to a track-crossing; but it is to be understood that with suitable changes readily suggestible to the skilled mechanic the improvement may also be applied to frogs, switches, and similar track structures.

Referring to the drawings, a , a' , a^2 , and a^3 45 represent the ends of four rails crossing each other, preferably at right angles. These rail-

sections a , a' , a^2 , and a^3 do not abut, but approach each other to form a substantially-rectangular opening in which a hardened-steel 55 block or crossing-piece b is adapted to be inserted to form a continuation of the bearing-surfaces of the various rail-sections. The manner in which this block or piece b is secured in place forms the main feature of the 60 present invention.

Referring now to Figs. 4 and 5, the rail-sections when properly placed form an opening d , in which is placed first the hardened plate b , which is elevated above the lower or 65 bearing faces of the rails a , a' , &c., by means of blocks or chips e . Into the upper portion of the opening d is then placed a core or chill f , the contour or shape of which is illustrated in perspective in Fig. 5, and in general terms 70 the core or chill consists of a plate or base f' , from which depend successive pyramidal-shaped blocks in the form of tapered step-like projections f^2 and f^3 . From the under face of the piece b extends a dovetail projection b' , which is by preference provided with 75 one or more hooks b^2 . In assembling the mold together prior to the pouring of the cast metal the rail-sections are up-ended and the core or chill f , block or piece b , and the wedges 80 e inserted, as illustrated in Fig. 4. A clay core g is now placed between the under side of the piece b , toward the projection f^3 of the core f , and this core g surrounds the hook b^2 and projection b' on the piece b and forms 85 also a continuation of the pyramidal projection f^3 of the core f . This clay core g is preferably baked directly upon the piece b and the hook b^2 prior to the insertion of the metal core f . The cast metal is then poured into 90 the opening d remaining and forms the cast section h , uniting the four rail-sections together. The metal core f and clay core g are now removed and the piece b elevated to come 95 flush with the bearing-face of the rails. The piece b when thus elevated is adjusted to position and held properly elevated by means of the chips or blocks e . (See Fig. 2.) In this position of the block or piece b there will be formed between the sides, base, and dove-tailed projection b' and the cast-metal section h , adjacent to these parts, a space which 100 gradually tapers or widens downward from the upper or bearing face of the block b to

the base of the dovetail b' . When properly centered, the piece b is held to position by a clamp m , (illustrated in dotted lines in Fig. 2,) and the crossing is then up-ended and the 5 face of the block b and surrounding parts are all highly heated. When in this heated condition, soft metal, such as zinc, is poured into the tapering space and, setting in said space, forms not only a cushion or seat n , upon 10 which the block b rests, but also a locking wedge-like connection n' , inserted between the dovetail b' and the adjacent portions of the cast section h . When the block b and adjacent parts cool, the whole structure 15 shrinks down upon the soft-metal cushion or seat n and wedge-like connection n' , thus firmly securing the block b in the cast section h of the structure. The clamp m can thereafter be disconnected from the structure.

20 Having thus described the nature and object of my invention, what I claim as new, and desire to secure by Letters Patent, is—

A railway-track structure, comprising rail-sections permanently secured together by a

cast-metal section having an opening at the 25 center or crossing-point of the rail-sections extending entirely through the cast-metal section, a hard-metal plate provided on its lower face with a dovetail projection adapted to fit into the opening in the cast-metal section below the seat of the plate in the cast-metal section, the upper face of said plate forming a continuation of the rail-sections, and a soft-metal lining interposed between the dovetail projection of the plate and the 30 adjacent parts of the cast section into which said projection is inserted, and said lining forming the means for securing the plate in the opening of the cast section, substantially as and for the purposes described.

In testimony whereof I have hereunto set my signature in the presence of two subscribing witnesses.

HENRY B. NICHOLS.
